UNITED STATES PATENT OFFICE.

FRANK J. WIESMAN, OF MONROE, MICHIGAN, ASSIGNOR TO THE WEIS FIBRE CONTAINER CORPORATION, OF MONROE, MICHIGAN, A CORPORATION OF SOUTH DAKOTA.

PAPER BOX.

1,406,707.

Specification of Letters Patent. Patented Feb. 14, 1922.

Application filed December 2, 1918. Serial No. 264,912.

To all whom it may concern:

Be it known that I, FRANK J. WIESMAN, a citizen of the United States, and a resident of Monroe, Michigan, have invented a certain new and useful improvement in Paper Boxes, of which the following is a specification.

This invention relates to paper boxes for holding tobacco or other similar commodities.

One object of the invention is to provide novel and improved means for closing the bottom of the box.

Another object is to provide novel and improved means for closing the top of the box.

It is also an object to provide certain details of construction tending to increase the general efficiency and the desirability of a box of this particular character.

To these and other useful ends the invention consists in matters hereinafter set forth and claimed.

In the accompanying drawings—
25 Fig. 1 is a perspective of a box embodying the principles of the invention, showing the top and bottom open.

Fig. 2 is a similar view showing the top and bottom closed.

30 Fig. 3 is a vertical section on line 3—3 in Fig. 2.

Fig. 4 is a vertical section on line 4—4 in Fig. 3.

Fig. 5 is a horizontal section on line 5—5 in Fig. 4.

Fig. 6 is a plan of the blank from which the box is made.

As thus illustrated, the blank comprises the rectangular side wall sections 1, 2, 3, 4, and 5, with a flap 6 for connecting the two ends of the blank together. The section 4 is provided at its upper edge with a flap 7 having a tongue 8, and the lower edge of this section is provided with a flap 9 having a flexible tongue 10, the latter being preferably scored one or more times at 11, thereby to make the tongue flexible. The upper and lower edges of the sections 3 and 5 are provided with short flaps 12 and 13, which are substantially rectangular, and which cooperate with said other flaps to form the closures for the top and bottom of the box, as will hereinafter more fully appear. The

section 1 has a half-moon-shaped opening 14 therein, and a small flap 15 at its lower edge.

In making the box, the section 1 is folded over upon the section 2, and the edge 16 of the section 1 is secured in place by glue or otherwise, so that a wall of double thickness is provided. Then the blank is folded to bring the strip or flap 6 inside of said double wall, and is glued or otherwise secured thereto, whereby a rectangular box is provided having relatively wide front and back walls formed by the sections 1, 2, and 4, and relatively narrow side walls formed by the sections 3 and 5, as shown in Fig. 1. Thereafter, the tongue 10 is bent or flexed upward and then inserted upward between the lower edges of the sections 1 and 2, the flap 15 facilitating this insertion by preventing the tongue 10 from being inserted inside of the box, instead of between the two thicknesses. The tongue 10 having been flexed as stated, it tends to spring into the opening 14 as soon as it is inserted far enough between the two thicknesses of the double wall. In this way the flap 9 is held against the bottom of the flaps 13 and 15, thereby tightly closing the bottom or lower end of the box. When the contents, such as tobacco, enters the box, the weight thereof will press the tongue 10 downward (see Fig. 3), thus folding it across the lower edge 17 of the opening 14, and forming a sort of lock to keep the bottom flaps closed.

The top of the box is closed by folding down the flaps 12, and by then inserting the tongue 8 downwardly between the sections 1 and 2, the outer thickness 2 being cut away or formed with a broad shallow notch at 18 to facilitate this insertion. In other words, the tongue 8 is bent downward against the outer surface of the upper edge portion of the thickness 1, and then slides downward inside of the thickness 2, much more easily than would be the case if both thicknesses were of the same height or were flush at their upper edges.

It will be seen that the box shown and described can be partially folded, leaving the top and bottom open, and then shipped in a flattened or crushed condition, thus avoiding waste space in shipment. The tobacco manufacturer or other user will then close the

bottoms of the boxes and after they are filled the tops will then be closed in the manner described.

The two thicknesses 1 and 2 hold the flap 8 between them, by the pressure exerted thereon, so that the box is held closed at the top. These two walls 1 and 2 also tightly clamp the tongue 10, the latter having a portion which is as wide as the flap 9, whereby displacement of the latter is more effectually prevented. The tongue 10 when folded, as shown in Fig. 3, forms a lock to very effectively hold the bottom of the box closed. When the contents of the box is poured out or removed, the tongue 10 can then be lifted, and the flap 9 and tongue 10 may then be pulled downward to open the box, if such is necessary. The entire box, however, is formed from a single blank made of paper 20 or other sheet material.

What I claim as my invention is:—

1. In a box, a double wall having an opening in the inner thickness thereof, so that said opening is covered, and a bottom flap 25 having a flexible tongue adapted for insertion between the two thicknesses and through said covered opening into position to be depressed by the contents of the box.

2. A box as specified in claim 1, said opening having a straight lower edge, and a curved upper edge and said tongue being adapted to engage said edge to lock the flap in position.

3. A box as specified in claim 1, said 35 tongue being creased transversely and thereby adapted to bend inward to enter said opening, and then downward upon the lower edge of said opening.

4. A box as specified in claim 1, said inner 40 thickness having a flap below said opening

to guide and facilitate the insertion of the tongue, which flap rests on the bottom of the box.

5. A structure as specified in claim 1, said box being formed in its entirety from a 45 single blank having said opening and tongue.

6. In a box made from a blank, the combination of side walls which are adjacent each other in the blank, a bottom wall, and a foldable flap having a flexible portion for 50 insertion between the side walls for attachment to the inner side wall to hold the bottom wall in place, having folded interlocking means to prevent withdrawal of the flap.

7. A structure as specified in claim 6, 55 said interlocking means involving provisions whereby said flap is folded and held against the inner surface of the inner side wall by the contents after the box is filled.

8. A structure as specified in claim 6, in combination with a provision to guide and facilitate the insertion of the flap, said provision being in the form of a flap which becomes a part of the bottom when the box is 60 formed.

9. A box blank comprising the vertical side walls for the box (1, 2, 3, 4, 5 and 6) the bottom wall of the box (9), flaps (13) for said bottom of the box, an opening (14) in one (1) of said vertical walls of the box, and a flexible flap (10) forming part of said bottom wall and adapted for insertion between two of said vertical walls (1 and 2) and through said opening into the box, all connected and arranged so that said two vertical walls (1 and 2) are adjacent to each other in the blank, substantially as shown and described. 75

FRANK J. WIESMAN.
